UNITED STATES PATENT OFFICE.

THOMAS WALTER HORN, OF CLEVELAND, OHIO.

INTERLEAVING DEVICE FOR PRINTING MACHINES.

Application filed June 7, 1926. Serial No. 114,095.

This invention relates to an interleaving device for printing machines by which slip sheets of absorbent paper are interleaved with the freshly printed sheets delivered from the printing machine to prevent smearing of the printed sheet and offsetting of the impressions from the printed sheet to the back of a superimposed printed sheet, the device of the present invention being herein illustrated as applied to a stencil machine of the rotary cylinder type.

It is the aim of the present invention to provide an interleaving mechanism which is simple in construction, inexpensive to manufacture, reliable in operation and easily attachable to standard printing machines.

A further object of the invention is to provide a slip feeding mechanism which will cooperate with the printing mechanism in such manner as to deliver the slip sheets on to the printed sheets without sliding of one sheet upon the other and consequently without smearing of the printed sheets.

A further object of the invention is to provide a slip sheet feeding mechanism which operates continuously and which delivers the slip sheets to the receiving receptacle substantially, simultaneously with the delivery of the printed sheets thereto.

A further object is to provide a slip sheet feeding attachment in which the slip sheet magazine is mounted directly above the printing mechanism in a position convenient for the operator and further to so mount the feeding attachment that it does not in any way interfere with the normal operation of the printing mechanism.

A further object is to so mount the slip sheet feeding attachment that it can be readily shifted to a position clear of the printing mechanism to permit access thereto.

With the above and other objects in view the invention may be said to comprise a device as illustrated in the accompanying drawings hereinafter described and particularly set forth in the appended claims together with such variations and modifications thereof as will be apparent to one skilled in the art to which the invention appertains.

Reference should be had to the accompanying drawings forming a part of this specification in which:

Fig. 1 is a side elevation of a stenciling machine with a slip sheet feeding attachment thereon.

Fig. 2 is a longitudinal vertical section through the stenciling machine and slip sheet feeding attachment.

Fig. 3 is a top plan view of a stenciling machine with a slip sheet feeding device thereon.

Fig. 4 is a side elevation of the cylinder and slip sheet feeder attachment.

In the accompanying drawings the present invention is illustrated as applied to a stenciling machine of the rotary cylinder type, the machine shown herein having a suitable supporting frame 1, a printing cylinder 2 and impression roller 3 yieldingly pressed against the under side of the cylinder 2 by means of a spring 4. The sheets to be printed upon are supported in a suitable magazine 5 and are delivered one at a time to the printing cylinder by suitable feeding mechanism including the feed roll 6 by which the sheets are advanced into the space between the cylinder 2 and the roller 3 from which the sheets are delivered into a suitable receiving receptacle 7 at the rear of the printing machine. The printing machine so far described is old and well known and a more detailed description thereof is therefore thought to be unnecessary, it being sufficient for the purpose of illustrating the present invention that the sheets of paper be taken one at a time from the magazine 5 be printed upon and delivered successively into the receiving receptacle 7.

The present invention consists of a device for delivering a slip sheet on top of each printed sheet delivered into the receptacle 7 and this slip sheet feeding device comprises a suitable magazine 8 which is adapted to be supported directly above the printing cylinder and suitable sheet feeding mechanism associated with this magazine for delivering the slip sheets on edge into the receptacle 7 in such manner that a slip sheet will be interposed between each pair of superimposed printed sheets.

The magazine 8 is provided with a downwardly off-set end portion 9 which is pivotally connected to a horizontal shaft 10 which extends between the upper rear ends of a pair of supporting arms 11 which are attached by clamps 12 to opposite sides of the frame 1 at opposite ends of the cylinder 2 and extend upwardly and rearwardly from the frame. The downwardly off-set portion 9 of the magazine 8 is provided on opposite sides with projecting retaining pins 13 which

bear against the upper edges of the supporting arms 11 and serve to support the magazine in either of two positions, the pins 13 engaging the arms 11 forwardly of the shaft 10 when the magazine is supported in its operative position shown in full lines in Figs. 1 and 2 and engaging with the arms 11 rearwardly of the shaft 10 to support the magazine in a position clear of the mechanism as shown in dotted lines in Figs. 1 and 4.

For delivering the slip sheets one at a time from magazine 8 a feed belt 14 is mounted in the downwardly offset forward portion 9 of the magazine and has its upper run in the plane of the bottom of the magazine 8 on which the stack of slip sheets is supported. The belt 14 runs over a large driven roller 15 and a small roller 16 and is provided with an intermediate idler roller 17. In order to increase the frictional drag of the feed belt on the slip sheets the belt, which is preferably made of rubber, may be provided with suitable raised projections 18. To insure the feeding of the sheets one at a time from the magazine 8 the edge of the stack of sheets adjacent the delivery end of the magazine is engaged by a pivoted gravity actuated follower 19 and in advance of the follower 19 there is a flexible wiper 20 which is preferably in the form of a strip of rubber provided with a metal bar 21 secured thereto along its forward edge, the wiper being supported on a crank arm 22 which is yieldingly pressed toward the belt by a spring 23, the wiper 20 engaging the belt directly over the supporting idler 17 and acting to hold back any sheets above the lowermost sheet which is being fed forwardly by the belt 14. At the delivery end of the belt 14 there is an adjustable deflector plate 24 which is supported upon the ends of the shaft carrying the roller 16 and retained in adjusted position by nuts 25 at the ends of this shaft. A spur gear 26 is fixed to the shaft of the roller 15 and this gear meshes with the gear 27 fixed to the shaft 10 upon which the magazine is pivotally supported, the gears 26 and 27 permitting the magazine 8 to be swung about the shaft 10 from operative to inoperative position. The shaft 10 is driven by means of a sprocket chain 28 which runs over a sprocket 29 fixed to the shaft 10 and over a sprocket 30 fixed to a shaft 31 which is in the gear train through which the printing mechanism is driven.

In the operation of the machine the printing cylinder is continuously driven and the sheets fed one at a time at intervals from the magazine 5 are printed upon and delivered into the receptacle 7. At the same time the feed belt 14 of the slip sheet magazine is also continuously driven and the slip sheets are fed one at a time from the slip sheet magazine. The sheets as they are delivered from

the magazine 8 pass over the adjustable deflector plate 24 and the edges thereof come into engagement with a curved guide projecting upwardly and forwardly from the rear end of the receptacle 7, this guide consisting of angle shaped guide bars 32 extending upwardly from the rear corners of the receptacle and one or more intermediate guide bars 30. The slip sheets are guided by the curved bars toward the rear end of the receptacle 7 and when the upper edge of the sheet passes the deflector plate 24 the sheet will fall forwardly on top of the sheet at the top of the pile in the receptacle 7. The operation of the belt 14 is so timed with respect to the rate of delivery of the printed sheets into the receptacle that a slip sheet is discharged from the magazine and delivered into the receptacle 7 substantially simultaneously with each printed sheet, the printed sheets being delivered horizontally into the receptacle 7 and the slip sheets at an inclination to the horizontal or on edge so that the printed sheets can enter completely into the receptacle 7 before the slip sheet falls from its inclined position to a horizontal position on the top of the pile, the intervals between the delivery of successive printed sheets into the receptacle 7 being sufficient to permit the slip sheets to fall into place on top of printed sheets in the receptacle.

The continuously operating slip sheet feeding device causes the sheets to be discharged at a uniform rate one immediately behind another and in order to properly time the delivery of the sheets the movement of the slip sheets from the magazine 8 into the receptacle 7 is slower than the movement of the printed sheets from the cylinder 2 into the receptacle, the more rapid movement of the printed sheets enabling them to move fully into the receptacle 7 while a slip sheet is falling into place from above. In a rotary stenciling machine such as shown herein about one half of the cylinder is used for printing and one sheet is so fed to the cylinder during each revolution thereof as to be engaged by the printing portion, the cylinder engaging each sheet during one half of its revolution so that the interval between delivery of successive printed sheets is substantially equal to the time of printing, in which case the speed of movement of the slip sheets toward the receptacle in one half that of the printed sheets.

The deflector plate 24 is made adjustable to insure the engagement of the rearmost edges of the slip sheets with the curved guide bars 32 and 33, the plate 24 being adjustable downwardly for relatively stiff sheets and upwardly for more flexible sheets. The guide bars 32 and 33 also cause the rearmost edges of the slip sheets to be accurately aligned with the rearmost edges of the

printed sheets and cause the slip sheets in falling to horizontal position to pivot about their rearmost edges and fall down upon the printed sheets without any relative sliding motion which would cause smearing of the printed sheets.

Although a preferred embodiment of the invention has been illustrated and described, it should be understood that the invention is not limited thereto and is susceptible of such modifications and adaptations as fall within the scope of the appended claims.

Having thus described my invention, I claim:

1. The combination with a printing machine having a receptacle for printed sheets at the rear thereof and means for printing and delivering sheets one at a time rearwardly to the receptacle, of a detachable slip sheet magazine supported above and forwardly of the rear end of said receptacle, and means formed as a unit with said magazine for feeding a slip sheet rearwardly therefrom to the receptacle simultaneously with each printed sheet.

2. The combination with a printing machine having a receptacle for printed sheets at the rear thereof and means for printing and delivering sheets one at a time to the receptacle, of a slip sheet magazine supported above and forwardly of the rear end of said receptacle, means for feeding the slip sheets one at a time rearwardly from said magazine simultaneously with the movement of the printed sheets, and forwardly inclined guides for said slip sheets extending upwardly from the rear end of said receptacle.

3. The combination with a printing machine having a receptacle for printed sheets at the rear thereof and mechanism for printing sheets and delivering the same one at a time into the receptacle, of a slip sheet magazine supported above and forwardly of the rear end of said receptacle, and mechanism carried by the magazine for continuously feeding the slip sheets into the receptacle at a slower speed than the printed sheets.

4. The combination with a printing mechanism, of a receptacle at the rear of said mechanism into which printed sheets are delivered by said mechanism, a slip sheet magazine supported above and forwardly of the rear end of said receptacle and continuously operating sheet feeding means associated with said magazine for delivering a slip sheet rearwardly and on edge into said receptacle simultaneously with each printed sheet and for guiding the slip sheets so as to hold them out of contact with the printed sheets while said printed sheets are entering the receptacle.

5. The combination with a printing machine having a printing cylinder, a magazine for sheets to be printed in front of said cylinder, a receptacle for printed sheets in the

rear of said cylinder and means for feeding the sheets one at a time from the magazine and past the cylinder into the receptacle, of a detachable slip sheet magazine supported on the printing machine above and forwardly of the rear end of said receptacle, and feeding means forming a unit with said magazine and driven from said machine for delivering slip sheets downwardly and rearwardly toward the rear end of said receptacle.

6. The combination with a printing machine having a printing cylinder, a magazine for sheets to be printed in front of said cylinder, a receptacle for printed sheets in the rear of said cylinder and means for feeding the sheets one at a time from the magazine and past the cylinder into the receptacle, of a slip sheet magazine supported on the printing machine above the cylinder and forwardly of the rear end of said receptacle, feeding means associated with said magazine and driven from said machine for delivering slip sheets rearwardly, and guiding means for causing them to be delivered substantially on end adjacent the rear end of the receptacle.

7. The combination with a printing machine having a printing cylinder, a magazine for sheets to be printed in front of said cylinder, a receptacle for printed sheets in the rear of said cylinder and means for feeding the sheets one at a time from the magazine and past the cylinder into the receptacle, of a slip sheet magazine supported on the machine above the cylinder, feeding means associated with said magazine and driven from said machine for delivering slip sheets to the receptacle, and guides extending upwardly and forwardly from the rear end of the receptacle for directing the slip sheets into the receptacle.

8. The combination with a printing machine having a receptacle for printed sheets, a printing cylinder and means for continuously feeding sheets past the printing cylinder and delivering the same into the receptacle, of a slip sheet magazine having feed mechanism driven from the printing machine, said magazine being mounted on the machine for movement from an operative position directly above the cylinder to an inoperative position clear of the cylinder.

9. The combination with a printing machine having a receptacle for printed sheets, a printing cylinder and means for continuously feeding sheets past the printing cylinder and delivering the same into the receptacle, of a slip sheet magazine pivoted to swing about a horizontal axis from a position directly over said cylinder to a position entirely to the rear thereof, feed mechanism carried by said magazine, and means for driving said feed mechanism from said machine.

10. The combination with a printing machine having a receptacle for printed sheets, a printing cylinder and means for continuously feeding sheets past the printing cylinder and delivering the same into the receptacle, of a slip sheet magazine mounted over the cylinder and inclined downwardly and rearwardly, guide members extending upwardly and forwardly from the rear end of the receptacle past the delivery end of the magazine, and feed mechanism carried by the magazine.
11. The combination with a printing machine having a receptacle for printed sheets, a printing cylinder and means for continuously feeding sheets past the printing cylinder and delivering the same into the receptacle, of a slip sheet magazine mounted over the cylinder and inclined downwardly and rearwardly, guide members extending upwardly and forwardly from the rear end of the receptacle past the delivery end of the magazine, feed mechanism carried by the magazine, means for driving said feed mechanism from said machine, and an adjustable deflector plate at the delivery end of the magazine.
12. The combination with a printing machine having a receptacle for printed sheets at the rear thereof and means for printing and delivering sheets one at a time to the receptacle, of a slip sheet magazine supported above and forwardly of the rear end of said receptacle, means for feeding the slip sheets one at a time rearwardly from said magazine simultaneously with the movement of the printed sheets, and guides adjacent the rear end of said magazine in the path of the rear edges of the slip sheets for guiding the rear edges of said sheets to the rear end of said receptacle.
13. The combination with a printing machine having a receptacle for printed sheets at the rear thereof and means for printing and delivering the sheets one at a time to the receptacle, of a slip sheet interleaving device comprising means for feeding a slip sheet on edge into the said receptacle in such manner that the sheet may then move from the on-edge position to the flat position upon top of a printed sheet, and means synchronizing such slip sheet feeding with the delivery of the printed sheets into the receptacle.
14. The combination with a printing machine having a receptacle for printed sheets at the rear thereof and means for printing and delivering sheets one at a time to the receptacle, of a slip sheet interleaving device comprising means for feeding a slip sheet on edge into the rear end of said receptacle, and means synchronizing such slip sheet feeding with the delivery of the printed sheets into the receptacle.
15. A slip sheet interleaving device adapted to be used with a printing mechanism of the type having a receptacle for the printed sheets at the rear thereof, and means for printing and delivering the sheets one at a time to the receptacle comprising a magazine for the slip sheets adapted to be connected to the printing mechanism, and means adapted to be operatively connected with the printing and delivering means of the printing mechanism for feeding a slip sheet on edge into the rear end of the receptacle for the printed sheets.
16. The combination with a printing machine having a receptacle for printed sheets at the rear thereof and means for printing and delivering the sheets one at a time to the receptacle, of a slip sheet magazine having feed means associated therewith and driven from said printing machine for feeding the slip sheets, and guiding means for causing the slip sheets to be delivered on edge adjacent the rear end of the receptacle.

In testimony whereof, I hereunto affix my signature.

THOMAS WALTER HORN.
